UNITED STATES PATENT OFFICE.

WILLIAM R. SMITH, OF BUFFALO, NEW YORK.

PIN-CLASP.

SPECIFICATION forming part of Letters Patent No. 776,763, dated December 6, 1904.

Application filed March 2, 1904. Serial No. 196,203. (No model.)

To all whom it may concern:

Be it known that I, WILLIAM R. SMITH, of Buffalo, in the county of Erie and State of New York, have invented certain new and useful Improvements in Pin-Clasps, of which the following is a specification.

This invention relates to a type of garment-fastening designed to either hold two articles of wearing-apparel in certain relative positions or to hold a portion of one garment in puckered or gathered condition. Several devices of this character have been heretofore produced in which there are prongs or spurs projecting in opposite directions and toward each other, which prongs or spurs are simply caught into the fabric and are retained therein by the arrangement of the opposite projection of the spurs or prongs. These devices will frequently serve to retain the garment or garments in the position desired, provided the latter is kept under sufficient tension to keep the fabric in certain engagement with the prongs or spurs.

The object of the present invention is to provide a device of this character having cloth-engaging points or angular projections at the back of the base member and adjacent to the fabric-engaging spurs, so that if the garment or garments to which the device is connected is loose or is shaken the said cloth-engaging points or angular projections will prevent the fabric from becoming disengaged from the spurs, the said points or angular projections, however, not being sufficiently rough to tear the fabric of the garment.

To these ends the invention consists in the construction substantially as hereinafter described and claimed.

Of the accompanying drawings, forming a part of this specification, Figure 1 represents a perspective view from the rear of a pin-clasp embodying my invention. Figs. 2 and 3 represent, respectively, front and longitudinal sectional views of the same. Fig. 4 indicates one of the uses to which the clasp is particularly adapted.

Similar reference characters designate similar parts throughout the several views.

The base member *a*, shown as consisting of

a plate having a front face capable of being 50 ornamented, has spurs *b*, rigidly secured to the rear face thereof. In Fig. 1 have shown two spurs at each end constructed of a piece of wire generally U-shaped and soldered at its middle to the back of the base member *a*, 55 the two ends of the wire being pointed and projecting parallel with the plate and toward the opposite end of the plate. Obviously, however, the number of spurs *b* may be increased or decreased without departing from the spirit 60 of my invention. It is also obvious that the said spurs may be integral with the base member, if desired.

In order that this device may be practically employed for such purposes as represented 65 in Fig. 4—that is, for drawing together different portions of a shirt-sleeve—I have provided means for preventing the accidental separation of the clasp if the tension under which the clasp is held be considerably relaxed or if the shirt-sleeve be even violently shaken. For this purpose I form a series of cloth-engaging points or angular projections *c* on the back of the plate *a* and under the spurs *b*. The said points or projections may 70 be formed in any suitable way. As represented in Figs. 1 and 3, they are quite similar in form to the usual teeth of a rasp and may be formed in much the same way—viz., by indenting the back of the plate by means of 75 a sharp-pointed tool driven thereagainst at an angle, so as to raise from the rear surface of the plate a series of somewhat sharp and inclined points. These points, however, are not 80 sufficiently sharp so as to produce a roughened surface that will be liable to tear cloth. It is my intention to form the back of the base member with a sufficient amount of 85 roughness adjacent to and underneath the spurs to prevent accidental disengagement of 90 the spurs from the fabric with which the pin-clasp is engaged. In order to practically secure this result, the points *c* at the two ends of the base are somewhat inclined in directions away from each other, the group at each 95 end being inclined in a direction to oppose disengagement of the cloth from the spurs adjacent thereto.

I claim—

1. A device of the character described, comprising a base member having rigid spurs at the back thereof, the spurs having penetrating-points projecting toward each other, the back of the base member under said spurs having cloth-engaging points, the said points at opposite ends of the base being inclined away from each other.
- 10 2. A device of the character described, comprising a flat base member having a plurality of rigid spurs at each end of the back there-

of, the spurs at each end having penetrating-points projecting toward the spurs at the other end, the back of the base member under the said spurs having cloth - engaging points, the said points at opposite ends of the base being inclined away from each other. 15

In testimony whereof I have affixed my signature in presence of two witnesses.

WILLIAM R. SMITH.
